UNITED STATES PATENT OFFICE

166,751

ELECTRIC HAIR CLIPPER

Alfonso Iannelli, Park Ridge, Ill., assignor to John Oster Manufacturing Company, Racine, Wis., a corporation of Wisconsin

Application February 7, 1951, Serial No. 14,129

Term of patent 14 years

(Cl. D22—5)

To all whom it may concern:

Be it known that I, Alfonso Iannelli, a citizen of the United States, residing at Park Ridge, in the county of Cook and State of Illinois, have invented a new, original, and ornamental Design for Electric Hair Clipper, of which the following is a specification, reference being had to the accompanying drawings, forming part thereof.

The dominant features of my design reside in those portions thereof shown in full lines.

I claim:

The ornamental design for an electric hair clipper, as shown and described.

ALFONSO IANNELLI.
